UNITED STATES PATENT OFFICE.

GABOR URR, OF PHOENIXVILLE, PENNSYLVANIA.

MATCH BOX.

Application filed August 7, 1928. Serial No. 127,815.

This invention relates to improvements in match receptacles and has reference to the type adapted to contain the ordinary household matches.

5 The primary object of this invention is to provide a device of the above mentioned character adapted to convert the ordinary match container into a useful household wall container, for the reception of matches and other 10 minute articles.

A further object of this invention is to provide a device of the above mentioned character, adapted to be unfolded to facilitate the device being hung on the wall of a 15 room or building.

A still further object of this invention is to provide a container for matches, which may be sold to the consumer all ready to be unfolded and attached to a wall in a home.

20 A still further object of this invention is to provide a device of the above mentioned type, which is neat in appearance and easy in operation, and construction.

With the above and other objects in view 25 which will appear as the nature of the invention is better understood, the same consists in the novel form, combination and arrangement of parts hereinafter more fully described, shown in the accompanying drawing and claimed.

30 In the drawing wherein like reference characters indicate corresponding parts throughout the several views,

Figure 1 is a vertical perspective view 35 showing the front wall of the container;

Figure 2 is a vertical perspective view showing the rear wall of the container and the vertical slot formed therein;

Figure 3 is a vertical perspective view 40 showing the box in its open and operative position with the flaps and ends in an open position; and

Figure 4 is a sectional view of the invention showing the manner in which the flaps are closed, and fastened together by a fastening bolt.

Referring more in detail to the accompanying drawing, there is illustrated a rectangular casing having front and rear walls 5, and side 45 walls 6. A longitudinally extending slot is formed in the rear wall of the casing and designated by the numeral 5^a. One of the side walls 6 is provided with a longitudinally extending strip of sand paper or other abrasive material 7 adapted to impart friction to the tip of the match for igniting the same.

A corresponding container of comparatively smaller size is slidably positioned or mounted within the outer casing and comprises the rear wall 8, and side walls 9 which 60 carry the end flaps 10, and 11 respectively.

One end of the inner slidable receptacle is closed by the corresponding flaps 10 and 11 being folded upon themselves, and fastened together by means of adhesive material 65 such as glue.

The opposite end of the inner container is adapted to be opened and closed at will and each of the opposite flaps 11, are provided with apertures 12, for the reception of a nut 70 and bolt 13 which passes through the rear wall flap 10. An auxiliary closing flap 14 is hingedly connected to the rear wall flap 10, by the hinge strap 15, passing through an opening 16 therein. The bolt 13 also serves 75 the purpose of holding the hinge strap 15, to the rear wall flap 10. An opening 17 is provided in the hinged flap 14, adapted to receive the nut and bolt 13 when the parts are in their closed position, as shown in Figure 4. 80

It will be noted that the opposite flaps 11 carried by the side walls 9 of the inner slidable container are adapted to be folded to overlap one another while the flap 10 hinged to the rear wall 8 of the rectangular 85 container is folded over the flaps 10 and is fastened thereto by the nut and bolt 13 passing through the several flaps. When the parts are in their closed position as shown in Figure 4 of the drawing the flap 14 is 90 hinged over the end flaps 11 and also receives the nut and bolt 13 for holding all of the flaps in their assembled position.

A nut 19 is fastened to the rear wall of the 95 slidable container 8 and passes through the slot 5^a, formed in the rear wall of the outer casing. A washer 20 is held between the lateral edges of the slot 5^a and the fastening nut 21, threaded on the other end of the machine screw 19 for holding the same in place. 100 It will be noted, that the length of the slot 5^a, formed in the rear wall, of the outer casing extends from the lower end of the rear wall, to midway thereof thereby limiting the movements of the inner container in respect to the 105 outer container as shown in Figure 3.

For a consideration of the operation of the device, attention is first called to Figure 4. The aforementioned figure shows the device in its closed position such as would be the 110 position when the container and contents were bought from the store or vender. After the

5 container and contents are delivered to the home of the user, the bolt 13 is unscrewed from the nut which is threaded on the other end and the flaps 11 and 10 are allowed to assume the position shown in Figure 3. The upper hinged flap 14 is then moved into the same plane as the flaps 10 to form a hanging support, as for a nail or pin passing through the opening 17, formed therein.

10 After the device has been hung on a wall the outer casing is slid downwardly, which brings the bolt 19 passing through the rear wall 8, of the inner receptacle to the end and extreme limit of the slot 5^a, formed in the rear wall 5 of the outer casing.

15 It is understood, that the parts and flaps of the inner container may be folded at any time, such as when it is desired to move the same into other positions or for packing purposes.

20 While there is herein shown and described the preferred embodiment of the present invention, it is nevertheless to be understood that minor changes may be made therein without departing from the spirit and scope of the invention as claimed.

25 What is claimed as new is:—

1. In a container of the type described, the combination with a rectangular casing open at each end and having a longitudinal slot formed in its rear wall, of a box slidably positioned in the casing, flaps on the rear and side walls at one end of the box fastened together by adhesive material, hinged flaps se-

cured to the opposite side walls and rear wall 35 of the other end of the box, an auxiliary flap having a hinged strap connection with the rear wall flap, a detachable bolt for holding the auxiliary flap hinge strap on the rear wall flap, when in an open position and adapted to 40 pass through the side wall flaps and the auxiliary flap when in closed position, and a bolt secured to the rear wall of the box passing through the longitudinal slot formed in the rear wall of the rectangular casing for limiting the relative movement of the box within 45 the casing.

2. In a container of the type described, the combination with a rectangular casing having a longitudinal slot formed in its rear wall, of 50 a box slidably positioned in the rectangular casing, flaps hinged to the rear and side walls at one end of the box and being fastened together, flaps hinged to the rear and side walls at the other end of said box, an auxiliary flap 55 hinged to the rear wall flap and having an opening formed therein adapted to receive a wall hook or the like, a detachable bolt for passing through the rear wall flap, side wall flaps and auxiliary flap for holding the same 60 in closed position, and a bolt fastened to the rear wall of said box and passing through the longitudinal slot formed in the rear wall of said rectangular casing adapted to limit the relative movement of the box within 65 the casing.

In testimony whereof I affix my signature.
GABOR URR.
